CLAIM

The ornamental design for a combined multi-outlet box with master switch and protective cover therefor, as shown and described.

DESCRIPTION

FIG. 1 is a perspective view of the combined multi-outlet box with master switch and protective cover therefor showing my new design, the cover being omitted for convenience of illustration;

FIG. 2 is a side elevational view thereof;

FIG. 3 is a top view thereof as seen from the plane indicated by line 3—3 in FIG. 2;

FIG. 4 is a front elevational view thereof;

FIG. 5 is a rear elevational view thereof;

FIG. 6 is a bottom plan view thereof;

FIG. 7 is a perspective view of the complete multi-outlet box and protective cover;

FIG. 8 is a bottom perspective view of the cover, the outlet box being omitted for purposes of disclosure.
